W. H. DOUGHTY

ROOF SUPPORT FOR MINES

Filed Feb. 11, 1924

FIG. 1

FIG. 2

FIG. 3

INVENTOR

W. H. Doughty

By W. E. Simler

ATTORNEY

UNITED STATES PATENT OFFICE.

WALTER H. DOUGHTY, OF MARTINS FERRY, OHIO.

ROOF SUPPORT FOR MINES.

Application filed February 11, 1924. Serial No. 691,866.

To all whom it may concern:

Be it known that I, WALTER H. DOUGHTY, a citizen of the United States of America, and resident of Martins Ferry, county of Belmont and State of Ohio, have invented certain new and useful Improvements in Roof Supports for Mines, of which the following is a specification.

This invention relates to supports for the roofs of mines, and more specifically to a roof header and supports therefor.

The primary object of the invention is to provide a header-like support for mine roofs having simple and practical means by which it is suspended in its place rather than superposed upon props in the manner usual to the timber headers commonly employed in mines.

A further object is to provide a metallic header of the character mentioned which is adapted to be supported either by means of suspension rods or by means of props.

In describing the invention in detail, reference is herein had to the accompanying drawings, in which—

Figure 1 is a cross section of a mine entryway, illustrating the application of my invention;

Figure 2 is an enlarged section on line 2—2, Fig. 1, showing the form of the header-suspension device; and—

Figure 3 is a view, similar to Fig. 1, of a room or passage of greater width, illustrating the header supported by props.

Referring to said drawings, 1 indicates a mine passage or tunnel which may be in the form of an entryway, corridor, or narrow room. Disposed in closely underlying relation to the roof 2 of said tunnel is a roof-

40 supporting header 3 consisting of a metal bar, herein shown as of flat rectangular form, which extends approximately from one side wall of the tunnel to the other. The opposite ends of said header are turned

45 downwardly and inwardly, forming inclined hook-like terminals 4, each of which is adapted to be engaged with the transverse end member 5^a of a substantially U-shaped rod 5 which serves as an anchoring device by

means of which the adjacent end of the 50 header bar is supported. Said anchor rod 5 has its parallel members 5^b disposed within bores 6 provided therefor in the overlying rock strata, said bores being outwardly and upwardly inclined from the angle between 55 the roof 2 and the adjacent side wall 7 of the tunnel, as shown. Said parallel anchor members 5^b have their ends turned laterally outward forming anchor lugs 5^c which are adapted to interlock with fillers 8 of concrete 60 or other suitable material tamped in said bores 6 following introduction therein of said anchor members.

In some cases it is practicable and preferable to employ props, as 9, Fig. 3, as supports for the header bars 3, as when the passage or tunnel spanned is of such great width that such props do not unduly restrict the width of the tunnel or interfere with the work. Such props are slightly 70 inclined in an upward and outward direction and have their upper ends disposed in seated underlying relation to the header bar and abutting the inner faces of the header terminals 4, as shown.

It will be noted that no amount of sagging of the intermediate portion of the header-bar 3 which may result from weight imposed upon said bar can result in disengagement of the terminals 4 from their supports, 80 whether such supports consist of the anchoring rods 3 or the props 9.

The employment of the structure which embodies the anchoring rods 3 is particularly advantageous in narrow corridors not only in that greater space is afforded for the passage of mine cars but also that such supports are not subject to displacement through derailing of cars and the like, as are the supporting props usually employed.

What is claimed is—

1. A roof support for mines comprising a metal bar for closely underlying the roof, said bar having downwardly extending hook-like end terminals, and an anchor-like suspension rod adapted to be engaged with said terminals and embedded in diagonally extending directions in the mine walls.

2. A roof support for mines comprising a metal bar for closely underlying the roof, said bar having downwardly extending hook-like end terminals, and a suspension rod for each end of said bar, said rod being of U-shape and adapted to have the transverse member thereof interengaged with the adjacent bar terminal and to have the parallel members thereof received in upwardly and outwardly inclined bores in the mine 10 walls, said parallel members having laterally directed anchor lugs formed on their ends for interlocking with a filler tamped in said bores.
- 5 In testimony whereof, I affix my signature.

WALTER H. DOUGHTY.
